SAFETY BELT BUCKLE

Wolf-Dieter Klink, Staufenstrasse 8, Lindach,
near Schwabisch Gmund, Germany

Filed Aug. 1, 1967, Ser. No. 8,077

Term of patent 14 years

U.S. Cl. D2—408
Int. Cl. D2—08

FIG. 5

FIG. 2

FIG. 3

FIG. 4

FIG. 1

FIG. 1 is a bottom perspective view of a safety belt buckle showing my new design, the hook portion being shown in broken lines and the broken line showing of a portion of a belt on either side of the buckle being for purposes of illustration only;

FIG. 2 is a side perspective view thereof; the hook portion of the safety belt buckle shown in broken lines in FIG. 1 being omitted for convenience of illustration;

FIG. 3 is a side perspective view of the side opposite that shown in FIGURE 2;

FIG. 4 is a rear elevational view thereof; and
FIG. 5 is a front elevational view.

I claim:

The ornamental design for safety belt buckle, substantially as shown and described.
